UNITED STATES PATENT OFFICE.

JOHN R. BOYD, OF GALENA, OHIO, ASSIGNOR OF ONE-FOURTH TO GUSTAV MEYER, OF WESTERVILLE, OHIO; ONE-FOURTH TO MICHAEL B. DRISCOLL, OF WASHINGTON, DISTRICT OF COLUMBIA; AND ONE-HALF TO CORA R. BOYD.

FIRE EXTINGUISHER.

Application filed January 19, 1927. Serial No. 162,115.

This invention has to do with fire extinguishers, and particularly with fire extinguishers in which the fire damping medium is carbon tetra chloride.

It is well known that chemically pure carbon tetra chloride has no affinity for metals and will not injure wood or fabrics. In other words, it may be said to be a neutral compound. It is, therefore, the ideal agent for use in fire extinguishers.

It is non-explosive and is a poor conductor of electricity. Because of these qualities it is especially valuable and safe in the case of fires involving explosive chemicals and those where live electric conductors are exposed.

The reason it has not come into more common use is the fact that it is not generally known, that, while it has a decided tendency to undergo a deteriorating change when for any considerable time subjected to air under pressure, it has no such tendency with air at atmospheric pressure. As a result of this lack of information, fire extinguishers designed to discharge carbon tetra chloride under pressure have uniformly failed to make proper provision for relief of the air pressure as soon as the flow of the carbon tetra chloride was stopped. The primary object of this invention is to do this. It consists of providing means whereby, when air under pressure is cut off from the carbon tetra chloride chamber, the compression is relieved and atmospheric pressure is quickly restored to said chamber. It is among the objects of the invention that such relief of pressure shall be effected automatically, and positively. It is also among the objects of this invention to provide a self-contained structure free from awkward joints, and of sufficiently strong material to withstand heavy pressure, and of such thickness as to reduce to a minimum any tendency for infiltration of air through the walls of the containing chambers. Still further it is of the objects of this invention to close the passage from the compressed air chamber to the carbon tetra chloride chamber with a non-leakable air valve, such as a "Kero test" valve, so that pressure may be retained indefinitely.

The structure whereby the above objects

are attained will be fully set forth and described later and in connection with the accompanying drawings, in which Fig. 1 is a top plan view of my extinguisher while

Figure 2 is a longitudinal section of my extinguisher taken on line 2—2 of Fig. 1, showing parts of the device in elevation.

Referring more specifically to the structure shown in the drawing it will be seen that my extinguisher is made as a compact unitary structure having a head 5 formed of forged steel with a depending flange-ring 6 about four inches wide, although this width will vary according to the capacity of the extinguisher, and a terminal flange 7 of approximately one-fourth the width of flange-ring 6. Tube 8 is forced into said flange-ring 6 and heavily brazed therein. This construction prevents spiderwebbing of the head 5 due to excessive heat if the tank or tube 8 were brazed directly to the head. Tube 9 is then forced over flange 7 and is brazed thereto. The opposite end of tank 8 is closed with a forged steel cup or dome 10 swaged and brazed therein, and at the same end of my device tank 9 is closed by a cup or dome 11 also swaged and brazed in place.

On head 5 are located the various operating parts of my invention.

These parts comprise a needle point valve 12 in communication with tank 9, a "Kero test" air control valve 13, and an air pipe 14 connecting these two valves. Mounted on the air pipe 14 is an air filler valve 15 for charging tank 8. Operatively connected with air control valve 13 by means of accurately cut gears 16 and 17 is a "Kero test" relief valve 18 mounted on the chloride tank 9. Valve 13 is provided with a handle 19. Gears 16 and 17 are so adjusted that valve 13 is opened and valve 18 is closed automatically, and vice versa. The port in relief valve 18 is relatively small. In actual practice it is about $\frac{3}{2}$ inch in diameter.

Carbon tetra chloride tank 9 is provided with a suitably capped filler opening 20, and discharge ports 21 and 22 controlled by valves 23 and 24. Connected with ports 21 and 22 are the usual take up tubes 25 and 26. Discharge hose 27 and 28 are connected with valves 23 and 24 respectively. Pres-

sure gauges 29 and 30 are mounted on tanks 8 and 9 respectively.

It has been found by experiment that better results are obtained by surrounding the 5 air tank with the carbon tetra chloride tank.

As is very desirable in a device of this character the mode of operation is very simple. The device being charged with both carbon tetra chloride and compressed air 10 the operator opens needle valve 12, then turns handle 19 thereby opening valve 13 and simultaneously closing relief valve 18. Pressure now being on the carbon tetra chloride, a stream is played on the fire 15 through either or both pieces of hose 27 and 28, the stream being controlled by valves 23 and 24 respectively.

As soon as the fire is under control, handle 19 is turned in a reverse direction, therefore 20 by closing valve 13. This shuts off the pressure from the carbon tetra chloride tank. At the same time relief valve 18 is opened, thereby permitting the pressure on the carbon tetra chloride to escape, thus restoring 25 atmospheric pressure to the carbon tetra chloride tank. It will be seen, therefore, that the one great objection to the use of carbon tetra chloride as a fire extinguishing medium has been removed, so that now this 30 valuable, though relatively inexpensive, agent is available to all. The function of needle valve 12 is to control the pressure on the carbon tetrachloride independently of valve 13.

35 In order to prevent explosion in case the fire extinguisher should be in the path of fire I have provided my extinguisher with fusible relief plugs 31 and 32. The walls of the tanks may be reinforced adjacent 40 to these plugs 31 and 32 if desired. It will be noted that this provision of fusible relief plugs will prove of material aid in the extinguishing of fires, even though early discovered, because plug 31 will melt first, then 45 plug 32, whereupon explosion of either the air tank or carbon tetra chloride, or both, will be avoided.

Having accurately described my invention, what I claim as new and desire to secure by 50 Letters Patent is:—

1. A fire extinguisher for using carbon tetra-chloride comprising, in combination, a solution tank, a valve-controlled discharge therefor, an air compression tank, means 55 providing a passage between said tanks, plural means for controlling air in said passage, and means operatively connected with one of said passage air controlling means

for restoring atmospheric pressure in the solution tank on closing the air passage. 60

2. A fire extinguisher for using carbon tetra-chloride comprising, in combination, a solution tank, an air compression tank mounted therein, a valve-controlled pipe connecting said tanks, a relief valve mounted on the solution tank, and means automatically operated by said control valve for opening said relief valve when said control valve is closed and vice versa. 65

3. A fire extinguisher for using carbon tetra-chloride comprising, in combination, a solution tank, a discharge hose therefor, a compressed air tank, a head for said tanks provided with integral brazing flanges secured to their respective tanks, means mounted on 70 said head providing a passage between said tanks, means for controlling air in said passage, and means mounted on the solution tank operatively connected with the means for controlling air in the air passage whereby opening the means for controlling air in the air passage will automatically close the means mounted on the solution tank and vice versa. 75

4. A fire extinguisher for using carbon tetra-chloride comprising, in combination, a solution tank, an air compression tank, a valve-controlled passage between said tanks and a relief valve for the solution tank operatively connected with the control valve 80 and so constructed that opening and closing the passage valve closes and opens, respectively, the relief valve. 85

5. A fire extinguisher for using carbon tetra-chloride comprising, in combination, a solution tank, a valve-controlled discharge therefor, an air compression tank, means providing a passage between said tanks, means for controlling air in said passage, and means operatively connected with said air control means whereby closing said means for controlling air automatically establishes atmospheric pressure in the solution tank. 90 100

6. A fire-extinguisher for using carbon tetra-chloride comprising, in combination, a solution tank normally under atmospheric pressure, a valve-controlled discharge therefor, an air compression tank, means providing a passage between said tanks, means for controlling pressure in said passage, and means on said solution tank operatively connected with said means for controlling pressure whereby closing of said pressure controlling means automatically re-establishes atmospheric pressure in the solution tank. 105

JOHN R. BOYD.
